UNITED STATES PATENT OFFICE

134,185

DESIGN FOR A BOTTLE CARRIER

Charles F. Belshaw, Greenville, Mich.

Application September 2, 1942, Serial No. 108,108

Term of patent 7 years

To all whom it may concern:

Be it known that I, Charles F. Belshaw, a citizen of the United States, residing at Greenville, in the county of Montcalm and State of Michigan, have invented a new, original, and ornamental Design for a Bottle Carrier, of which the following is a specification, reference being had to the accompanying drawing, forming a part thereof, in which:

I claim:

The ornamental design for a bottle carrier, as shown.

CHARLES F. BELSHAW.
